(57) **CLAIM**

The ornamental design for a goggle lens, as shown and described.

DESCRIPTION

FIG. 1 is a rear, top, and right side perspective view of the new design for a goggle lens;

FIG. 2 is a front and right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front, top, and left side perspective view illustrating the goggle lens of FIGS. 1–8 assembled into a goggle;

FIG. 10 is a front view thereof;

FIG. 11 is a rear view thereof;

FIG. 12 is a right side view thereof;

FIG. 13 is a left side view thereof;

FIG. 14 is a top view thereof; and,

FIG. 15 is a bottom view thereof.

The broken lines shown in the drawings illustrate portions of the goggle lens and environmental structure and form no part of the claimed design.

In the absence of surface shading, the claim is understood to be limited to the shape and configuration as shown by the outlines and to exclude all other aspects of the surface appearance.

1 Claim, 9 Drawing Sheets
